UNITED STATES PATENT OFFICE

FRANK ABRAM TITTEMORE, OF RICHMOND, CALIFORNIA, ASSIGNOR TO HOPKINS SPRAY EQUIPMENT COMPANY, OF SAN FRANCISCO, CALIFORNIA, A CORPORATION OF NEVADA

PAINT-SPRAYING MACHINE

Application filed June 2, 1928. Serial No. 282,325.

This invention relates to a combined pressure controlling and water separating device for paint spraying machines.

One of the objects of this invention is to provide a combined pressure controlling and water separating device for paint spraying machines which is simple in structure, efficient in operation, compact and convenient for use and application.

10 A further object of this invention is the provision in a unitary structure of means for use in a paint spraying machine for supplying fluid pressure to the paint container and spray nozzle under controlled pressure conditions and for removing the moisture from the fluid pressure to prevent its mixing with the paint.

15 A further object of this invention is the provision of a structure of the above type for detachable engagement with a paint pot by means of which all of the elements may be easily applied to and removed from the paint pot as a unitary structure.

20 A further object of this invention is the provision of an improved structure which is very simple for effecting the removal of the moisture from the fluid pressure medium before it is admitted to the paint pot.

25 These and other objects as will appear from the following disclosure are secured by means of the invention.

30 This invention resides substantially in the combination, construction, arrangement and relative location of parts all as will more fully appear hereinafter.

Referring to the drawings,

Figure 1 is a vertical cross-sectional view through the device of this invention showing some of the parts in front elevation.

40 Figure 2 is a cross-sectional view taken on the line 2—2 of Figure 1 looking in the direction of the arrows.

45 In the operation of paint spraying apparatus employing a spray gun for applying the paint to surfaces it is usual to feed the paint to the spray gun from a closed receptacle by means of fluid pressure and to supply fluid pressure to the paint gun for the purpose of atomizing the paint and directing it 50 upon the surface to be covered. In the cor-

rect operation of such a device the fluid pressure supplied to the paint container is different in amount from the fluid pressure of the medium supplied to the spray gun.

Furthermore, the amount of the fluid pressure supplied to the paint container varies with the viscosity of the paint as well as with the height of the spray gun above the level of the paint in the container. The fluid pressure supplied to the spray gun varies in amount depending upon the degree of atomization required, upon the viscosity of the paint, and upon the rate at which it is desired to apply the paint to the surface. These and other incidental considerations require that the pressure of the medium supplied to the paint container and to the spray gun must be under ready control so that the correct operating conditions may be maintained.

It has been found in practice that the moisture which is condensed in the fluid pressure medium, which is usually air, by reason of the compression thereof, interferes with the proper operation of the apparatus if it is permitted to mix with the paint. Besides following the spray gun the moisture mixed with the paint prevents it from forming a smooth coat on the surface being covered. It is the purpose of this invention to provide a simple structural unit by means of which the moisture may be removed from the air before it reaches the paint container and the spray gun and by means of which the pressure of the air supplied to the container and the spray gun may be readily coordinated to insure the correct operation of the entire apparatus.

Referring to the drawings which show one form of device embodying the principles of this invention, there is shown at 1 a paint pot or container having a removable plug 2 for closing and opening through which the paint may be supplied to the container. The container is provided at the top with a screw-threaded opening by means of which the unit 3 comprising the features of this invention is attached to the container. The unit is provided with a screw-threaded extension 4 which engages the threads of the opening in the container and by means of which an air

tight joint is made. The unit 3 is provided at its top with a threaded extension 5 intended to receive the internally threaded nut 7 which, together with the packing material 6, provides a packing gland around the rod 8 which extends through the nut 7 and the unit 5 so as to project into the container 1. The lower end of the rod 8 is provided with a paddle or stirrer 9 by means of which the paint may be maintained in its correctly mixed condition.

The upper portion of the unit 3 comprises a casing 10 which forms a chamber 11 between it and the inner sleeve through which the rod 8 passes. The inner wall of the casing 10 is provided with a spiral groove 12. A threaded port 13 is provided in the wall of the casing 10 which delivers into the spiral groove 12 on the interior of the casing. At 14 is shown a threaded opening near the bottom of chamber 11 which is intended to receive the drain cock 15. Near the top of casing 10 to one side thereof is attached a nipple 45 which connects with a pressure reducing valve 16 having the regulating handle 17. This pressure reducing valve may be one of the many well known types on the market and does not of itself form any part of this invention.

Mounted on the top of the pressure reducing valve 16 is a pressure gauge 18 which gives a visual indication of the pressure delivered from the valve. The fluid pressure medium in the valve is delivered therefrom through the pipe 20 which opens into the chamber 21, which chamber extends partially around the central sleeve in arcuate form. This chamber 21 is not in communication with chamber 29 which is of similar construction to it. At 22 is shown a threaded nipple by means of which the hose or pipe leading to the spray gun may be attached.

Another nipple 23 connects the chamber 11 near the top thereof with a second pressure reducing valve 24 having the control handle 25. As before a pressure gauge 26 gives a visual indication of the reduced pressure of the fluid pressure medium delivered from the valve. The outlet of valve 24 is connected to a T 27 which is united at one end by means of the pipe 28 with the chamber 29. This chamber 29 opens through a splash nozzle 30 into the interior of the container 1. The other end of the T 27 is connected by means of a pipe 31 to a safety or blow-off valve 32.

A description of the invention in operation will be given. The container 1 is supplied to a suitable height with the paint to be sprayed through the opening in the container closed by the plug 2. From time to time the paddle 9 is moved to keep the paint correctly mixed. The fluid pressure medium, usually air, is supplied to chamber 11 through the port 13. The air entering the port 13 at a high velocity travels spirally within the chamber 11 by means of the groove 12 tending to remain

therein by reason of the centrifugal forces acting thereon because of its tangential delivery to the chamber.

The water vapor in the air particularly follows the path of the groove 12 and collects at the bottom of chamber 11 from which it may be removed periodically by means of the drain cock 15. The purged air then travels through the pipes 45 and 23 to the pressure reducing valves 16 and 24, respectively. The air then passes through the pipes 20 and 28 to the chambers 22 and 29 respectively, with which they are in communication. The pressure of the medium delivered to these chambers is coordinated and regulated to the correct value by means of the pressure reducing valves 16 and 24. The gauges 18 and 26 give a visual indication of this pressure. The air supplied to chamber 29 is admitted to the container 1 through the splash nozzle 30. The paint is then delivered under air pressure from the container 1 at any suitable point, not shown, to the spray gun, all as is well known in this art. The air pressure supplied to chamber 21 is delivered through pipe 22 to the spray gun by means of a hose or other suitable conduit. If, for any reason, an excessive pressure should be built up in the container 1 this pressure is relieved by means of the safety valve 32 and the splash nozzle 30 is provided to prevent any paint escaping from the container 1 to the safety valve.

It will be apparent from the foregoing disclosure that I have provided an improved unitary structure by means of which air under the proper pressure conditions may be supplied to the paint container and to the spray gun without permitting the admission of moisture to either. The device is also constructed so that the moisture may be collected at a point where it will do no harm and be removed from the apparatus from time to time.

I am well aware that many changes in the detail of construction and relative association of parts will occur to those skilled in this art and I do not, therefore, desire to be particularly limited to the construction shown in the drawings but rather to the scope of this invention as it is defined below.

Having now set forth the objects and nature of my invention and a structure embodying the principles thereof what I claim as new and useful and of my own invention and desire to secure by United States Letters Patent is:

1. In a paint spraying apparatus including a paint container the combination comprising a combined pressure regulating and water separating unit comprising a chamber having means formed on the inner wall thereof for separating the moisture from the compressed air delivered thereto, and adjustable

pressure regulating devices supported on and in communication with said chamber.

2. In a paint spraying apparatus employing a paint container the combination comprising a detachable unit for the container constructed to form a chamber, said chamber having spiral grooves on the interior wall thereof and a port opening into said spiral groove through which compressed air may be delivered to the chamber, and a drain cock at the bottom of the chamber for permitting the removal of the accumulated moisture from the chamber.

3. In a paint spraying apparatus, including a paint container, the combination comprising a unitary structure attachable to the container, arranged to form three independent chambers, one of said chambers having a spiral groove on the inner wall thereof, means forming a passage from said chamber to each of the other chambers, said means including a pressure regulating valve, and means for providing communication between one of said chambers and the interior of the container.

4. In a paint spraying apparatus, having a paint container, a combined pressure regulating and moisture separating device comprising a single unit having three chambers, one of said chambers having a groove on the inner wall thereof into which the moisture laden air is delivered under pressure, a drain cock in communication with said chamber near the bottom thereon, and conduits connecting said chamber with each of the other chambers, said conduits having pressure regulating means therein, one of said other chambers being in communication with the paint container.

5. A structural unit of the type described comprising a member forming a chamber, said chamber having a spiral groove on the inner wall and a port delivering tangentially into the chamber in alignment with the groove, and a drain cock supported on said member and communicating with the bottom of said chamber.

6. In a device as described, the combination comprising a member forming three chambers, one of said chambers having a spiral groove on the inner wall thereof and a port opening tangentially into the chamber in alignment with the upper end of the groove, a plurality of pressure regulating means supported on said member all of which communicate with the chamber having the groove and one of which communicates with one of the other chambers and the other of which communicates with the third chamber, and a safety valve supported on said member and in communication with said third chamber.

7. In a paint spraying apparatus, including a paint container, a structural unit comprising a member forming three chambers, one of

said chambers having a spiral groove on the inner wall thereof, and a port opening tangentially into the chamber in alignment with the upper end of the groove, a plurality of pressure regulating means supported on said member all of which communicate with the chamber having the groove and one of which communicates with one of the other chambers and the other of which communicates with the third chamber, said third chamber being in communication with the paint container and a splash nozzle forming the communicating means.

8. In a paint spraying apparatus, including a structural unit detachably secured to a paint container for regulating the pressure medium and separating the moisture from the medium comprising the combination, of a member having three chambers therein and central bore extending therethrough and opening into the container, means supported in said bore for stirring the contents of the container, means formed on the inner wall of one of said chambers for removing the moisture from the air supplied thereto, a drain cock supported on said member for removing the moisture for said grooved chamber, means including pressure regulating valves connecting said grooved chamber with each of the other chambers, and a splash nozzle for connecting one of said chambers with the container.

9. In a paint spraying apparatus, including a structural unit detachably secured to a paint container for regulating the pressure medium and separating the moisture from the medium comprising the combination, of a member having three chambers therein and central bore extending therethrough and opening into the container, means supported in said bore for stirring the contents of the container, means formed on the inner wall of one of said chambers for removing the moisture from the air supplied thereto, a drain cock supported on said member for removing the moisture for said grooved chamber, means including pressure regulating valves connecting said grooved chamber with each of the other chambers, a splash nozzle for connecting one of the chambers with said container, and means for relieving the paint container of excess pressure through said splash nozzle whereby the liquid in the container cannot escape through the pressure relieving means.

In testimony whereof I have hereunto set my hand on this 29th day of May A. D. 1928.

FRANK ABRAM TITTEMORE.
